VALVE MECHANISM FOR CONTROLLING A DRIER

Filed Jan. 27, 1934

UNITED STATES PATENT OFFICE

2,062,126

VALVE MECHANISM FOR CONTROLLING
A DRIERGeorge M. Gibson, Waterloo, Iowa, assignor to
National Metal Products Company, Waterloo,
Iowa, a corporation of Iowa

Application January 27, 1934, Serial No. 708,640

5 Claims. (Cl. 121—46.5)

This invention relates to improvements in mechanism for operating and controlling driers, and particularly that type of drier used in connection with domestic washing machines, and in which is employed fluid under pressure for operating the same, the drier being of that type employing a rigid container in which is supported a flexible waterproof clothes container adapted to receive clothes to be dried, and capable of being partially collapsed to squeeze the water from the clothes by fluid under pressure forced between the sides of the drier and the clothes container, suitable means being provided for discharging the water from the clothes into the washing machine.

Heretofore various types of pumps have been used to deliver the fluid to the clothes drier for the purpose of collapsing the clothes container. These pumps work quite satisfactorily if proper attention is given them from time to time. The initial cost of manufacture is also quite high.

I find that a large number of the cities and towns have water systems which operate under a considerable pressure, varying from 30 pounds to 150 pounds per square inch, and that water from the ordinary piping system such as installed in the ordinary residence and having a pressure above 30 pounds to the square inch may be utilized to advantage to provide pressure to operate driers of the type above described.

It is, therefore, the object of my invention to provide a simple, durable and reliable valve mechanism which may be used in place of the pump for applying pressure to the drier, and in connection therewith is provided a simple and reliable means for controlling the flow of water from the water system to the drier and from the drier to the point of discharge, and in which is included suitable means for easily and quickly attaching the valve mechanism to the faucet of the ordinary piping system.

A further object of my invention is to provide an improved pressure regulating and reducing device which may be easily and quickly attached to the ordinary drier of the fluid operated type above described, and in which is employed a single manually controlled device so arranged that when the pressure reducing mechanism is attached to the faucet of the water system, then the operator may easily and quickly apply the pressure to the drier when so desired, and also accomplish the release of said pressure.

A further object is to provide in a fluid controlled device of the type above described, means whereby a predetermined pressure within the

drier may be automatically maintained even if the supply pressure varies considerably.

My invention consists in the construction, arrangement and combination of the various parts of the device, whereby the objects contemplated are attained, as hereinafter more fully set forth, pointed out in my claims, and illustrated in the accompanying drawing, in which:

Figure 1 is a vertical longitudinal sectional view of my improved valve mechanism showing the valves in position to permit fluid under pressure to enter the pressure chamber, with exhaust valve closed.

Figure 2 is a longitudinal sectional view of the valve mechanism for controlling the flow of water to and from a drier of the type above described, the valves being in a normal position with the water shut off from the drier.

Figure 3 is a longitudinal sectional view of same showing the valves in the position they would assume when pressure is being applied to the drier and automatically maintained at said pressure.

Figure 4 is a detail end view of the lever mechanism for operating the valve.

Referring to the accompanying drawing, I have used the reference numeral 17 to indicate the valve casing in which one end of the pipe 15 leading to drier mechanism is connected. A discharge pipe 18 is connected in the upper end of the casing 17 to which a hose may be connected, the end of which may lead to a sink or to a drain in the floor on which the washing machine is supported. The bottom end of the casing 17 is provided with a pipe 23 to which a suitable hose 30 to supply water under pressure is connected.

The casing 17 is secured to the supporting frame of a washing machine tub by means of suitable brackets 27. The bottom of the casing 17 is provided with a screw threaded opening in which is mounted a plug 29 having a vertically arranged bearing 30. The upper end of the casing 17 is provided with a screw threaded opening 31 in which is mounted a bushing 32. The upper end of the bushing is provided with an upwardly 40 extending pipe 33 and having its lower end closed and provided with an opening 34.

The casing 17 is provided with a contracted portion 35 having a valve opening 36 and also a partition 37 provided with an opening 38. The partition 37 and the contracted portion 35 provide means for dividing the casing into an inlet chamber 39, a pressure chamber 40 and a discharge chamber 41. The walls of the chamber 41 have a discharge opening 42 in which the pipe 18 is con- 55

nected, the walls of the chamber 40 are provided with an opening 43 for receiving the pipe 16, while the wall of the chamber 39 is provided with an opening 44 for receiving the pipe 23.

5 Supported longitudinally through the center of the casing 17 I have provided a valve stem 45, the lower end of which is contracted and slidably supported in the bearing 30. The upper end of the valve stem 45 is provided with a head 46 slidably mounted in the pipe 33. The lower end of the enlarged portion of the valve stem 45 is provided with a screw threaded portion 47.

10 The screw threaded portion 47 supports valve members 48, 49 and 50, said valve members being formed preferably of yieldable material such as 15 leather or rubber. The valve members 48 and 49 are separated by a washer 51 and secured in position by means of suitable nuts 52, while the valve member 50 is secured in position by means of 20 nuts 53.

25 Slidably mounted in the opening 36 is a sleeve 54 having an outwardly extending flange 55 at its upper end designed to rest on the upper end of the contracted portion 35 when the sleeve is at its lower limit of movement. The lower end of the sleeve has an inwardly extending annular flange 56 for forming a valve seat. A discharge opening 57 is formed in said flange. A spring 58 has its lower end carried by the flange 56 and its 30 upper end resting against the lower end of the bushing 32, while a spring 59 has its lower end resting on the lower end of the bushing 32 and its upper end against the under surface of the head 46.

35 The valves 48, 49 and 50 are supported normally in the position illustrated in Figure 2, with the valve member 49 resting on the valve seat 60 formed on the upper surface of the member 37 with the valve 50 near the lower end of the chamber 39. The sleeve 54 is forced downwardly by 40 means of the spring 58 with its lower end terminating in the chamber 40 and above the valve 48 a considerable distance.

45 The valve 49 is held against its seat by forcing the rod 45 downwardly against the tension of the spring 59 by means of a lever controlled mechanism comprising a spring 61 resting on the upper end of the head 46 and placed under tension by means of a head 62 also slidably mounted in the 50 pipe 33 and operated by a rod 63 extending upwardly through a packing gland 64 in the upper end of the pipe 33.

55 The upper end of the rod 63 is connected to a head 65 slidably mounted in a pipe 66 secured to the upper end of the packing gland 64. The upper end of the rod 63 is pivotally connected to a link 67 forming the lower side of a lever device 68. Said lever device 68 includes link members 69 pivotally connected to the upper end of the 60 pipe 66. The member 68 is provided with an operating handle 70. The packing gland 64 is provided with a slidable member 71 resting on top of the packing 72. A spring 73 has its lower end resting on the member 71 and its upper end against the head 65.

65 The spring 73 creates a downward pressure on the member 71 which is slidably mounted in the pipe 66 and thereby applies pressure to the packing 72 so that a tight joint is always provided 70 around the shaft 63. The spring 73 also imparts a lifting force to the head 65 in such a manner as to support the handle 70 in an elevated position when unlocked, and in turn the head 62 also supported in an elevated position as shown in 75 Figure 3.

The links 67 and 69 are so arranged that the shaft 63 is locked at its lower limit of movement when the handle 70 is in its lowered position illustrated in Figure 2, said parts being locked with the rod 63 at its lower position of movement 5 on account of the pivotal connection between the member 67 and the links 69 passing to the right of a dead center line common to the pivotal connection between the links 69 and the pipe 66 and the pivotal connection between the link 67 and the rod 63, at which time the outer end of the member 68 will engage the upper end of the pipe 66 and thus limit the downward movement of said lever.

When the head 62 is moved to its lowered position of movement, as shown in Figure 2, pressure will be applied to the spring 61, which in turn will apply pressure to the head 46 and the rod 45, causing the valve 49 to engage the seat 60 with the valve 48 spaced below the flange 56 of the sleeve 54 with the valve 50 below the partition 37. This is the normally closed positions of the valves.

Assuming that the pipe 23 has been connected to suitable water supply under pressure, then water under pressure will enter the pipe 23 and 25 the inlet chamber 39. Assuming that it is desired to supply water to the drier for operating the same, then the operator grasps the lever 70 and moves it upwardly, permitting the spring 73 to lift the head 65 to the position illustrated in 30 Figure 3, after which the spring 59 will lift the head 46 causing the valves 48, 49 and 50 to be elevated to the positions shown in Figure 1, with the valve 48 against the flange 56 of the sleeve 54.

Water will then flow upwardly through the 35 opening 38 and around the threaded portion of the rod 45 into the pressure chamber 40. The valve 48 will prevent water from passing through the opening 57. Pressure will then be built up on the pipe 16 and in the space 15 between the 40 drier and the clothes container until the said pressure equals the resiliency of the spring 58.

Further pressure development in the pressure chamber will cause the sleeve 54 to be moved 45 upwardly and in turn the valve 50 until the said valve 50 engages the valve seat 74 in the member 37, at which time the flow of water from the chamber 39 will cease with the water in the chamber 40 having the desired pressure to operate the drier.

50 When the clothes have been properly dried, the handle 70 is then moved downwardly, causing the valve 49 to be moved to position on its seat 60 and the valve 48 to be separated from the flange 56, after which water from the drier will be forced upwardly through the opening 57 into the chamber 41 and from there to the discharge pipe 18.

55 Thus it will be seen that I have provided a 60 control device which is of comparatively simple construction and which may be easily attached to a clothes drier of the type above described, which is reliable and accurate in its operation, and in which the entire operation of the device 65 may be controlled by a single lever and at the same time provides means for automatically maintaining a predetermined pressure in the pressure chamber. Said predetermined pressure may be varied by adjusting the bushing 32 in the casing 17, said bushing being locked in its adjusted position by means of a lock nut 76.

70 The spring 61 provides means whereby adjustable and yieldable pressure will always be maintained between the valve 49 and its seat 60, even 75

if the valve seat and the valve are worn a considerable amount.

Sometimes it is desired to fill the washing machine tub to which the drier is attached with water from the supply pipe 23. At such times the operator simply places one end of a hose connected to the discharge pipe 18 in the upper end of said tub and then elevates the lever 70 a slight amount, just enough to unseat the valve 49 without closing the valve 48 and its coating seat. Water will then flow upwardly through the opening 38 into the chamber 40, thence through the opening 57 into the chamber 41, and then into the pipe 19 and finally to the tub 10, thereby providing means whereby water may be delivered from the faucet 25 to the tub without having to actuate a valve in said water supply pipe, and thus providing a single control for both supplying water to a washing machine tub and other containers.

In actual practice the diameter of the threaded portion of the shaft 45 and the size of the opening 38 should be such as to provide a restricted passage so that a considerable pressure drop will result between the chambers 39 and 40 when the valves are at their maximum open position, to prevent vibration or hammering of the valve 48 as it is moved to a closed position.

I claim as my invention:

1. In a device of the class described, a casing provided with a pressure chamber having inlet and outlet passages; a sleeve supported in the outlet passage to slide toward or from said pressure chamber, its inner end having a valve seat; yieldable means for imparting movement to said sleeve toward said pressure chamber; a valve rod mounted through said sleeve and passages; an exhaust valve carried by said rod adapted to first close said outlet passage upon movement of said rod in one direction; an inlet valve also carried by said rod to close the inlet passage on further movement of said rod in the same direction; yieldable means for moving said rod to closed position; a third valve carried by said rod for closing the inlet passage with exhaust valve open when the rod is moved in the opposite direction; and manually operated means for controlling the opening and closing movements of said rod.

2. In a device of the class described, a casing provided with a pressure chamber having inlet and outlet passages; a sleeve supported in the outlet passage to slide toward or from said pressure chamber, its inner end having a valve seat; yieldable means for imparting movement to said sleeve toward said pressure chamber; a valve rod mounted through said sleeve and passages; an exhaust valve carried by said rod adapted to first close said outlet passage upon movement of said rod in one direction; an inlet valve also carried by said rod to close the inlet passage on further movement of said rod in the same direction; yieldable means for moving said rod to closed position; a third valve carried by said rod for closing the inlet passage with exhaust valve open when the rod is moved in the opposite direction; manually operated means for control-

ling the opening and closing movements of said rod; and yieldable means for locking the rod in its last position of movement.

3. In a device of the class described, a casing provided with a pressure chamber having inlet and outlet passages; a sleeve supported in the outlet passage to slide toward or from said pressure chamber, its inner end having a valve seat; yieldable means for imparting movement to said sleeve toward said pressure chamber; a valve rod mounted through said sleeve and passages; an exhaust valve carried by said rod adapted to first close said outlet passage upon movement of said rod in one direction; an inlet valve also carried by said rod to close the inlet passage on further movement of said rod in the same direction; yieldable means for moving said rod to closed position; a third valve carried by said rod for closing the inlet passage with exhaust valve open when the rod is moved in the opposite direction; manually operated means for controlling the opening and closing movements of said rod; and means for varying the tension of the first yieldable means.

4. In a device of the class described, a casing provided with a pressure chamber having inlet and outlet passages; a sleeve supported in the outlet passage to slide toward and from said pressure chamber, its inner end having a valve seat, yieldable means for imparting movement to said sleeve toward said pressure chamber, an exhaust valve adapted to close the outlet passage; a second valve for closing the inlet passage after the exhaust valve has been closed and a predetermined pressure has been established in said pressure chamber and the first valve has been moved outwardly against the yieldable means for closing the same, yieldable means for moving said exhaust valve and the second valve to a closed position; a third valve for closing the inlet passage when the exhaust valve is in an open position; and manually operated means for moving the last valve to a closed position.

5. In a device of the class described, a casing provided with a pressure chamber having inlet and outlet passages; a sleeve supported in the outlet passage to slide toward and from said pressure chamber, its inner end having a valve seat; yieldable means for imparting movement to said sleeve towards said pressure chamber, an exhaust valve adapted to close the outlet passage; a second valve for closing the inlet passage after the exhaust valve has been closed and a predetermined pressure has been established in said pressure chamber; yieldable means for moving said exhaust valve and said second valve to a closed position; a third valve for closing the inlet passage when the first valve is in an open position; manually operated means for moving the last valve to a closed position; and means for locking the valve closing means in a closed position, the last said means including a spring for applying yieldable pressure between the valve and the seat.
